UNITED STATES PATENT OFFICE.

CHARLES THOMAS MASON, OF SUMTER, SOUTH CAROLINA, ASSIGNOR TO SUMTER ELECTRICAL COMPANY, A CORPORATION OF SOUTH CAROLINA.

IGNITION-DYNAMO.

1,126,676.

Specification of Letters Patent. Patented Jan. 26, 1915.

Application filed July 26, 1913. Serial No. 781,414.

To all whom it may concern:

Be it known that I, CHARLES THOMAS MASON, a citizen of the United States, residing at Sumter, in the county of Sumter and State of South Carolina, have invented certain new and useful Improvements in Ignition-Dynamos, of which the following is a specification, reference being had to the accompanying drawing.

10 My invention relates to dynamo electric machines, and particularly those machines which are used in ignition systems for gas engines and the like.

Specifically it has to do with the design and arrangement of a high tension magneto type of dynamo machine. Heretofore machines of this type have been of necessity complicated, with many parts, difficult to adjust, and very liable to get out of order.

20 With these objections in mind, I have heretofore invented an improved type of machine, which is disclosed and claimed in my prior application Serial No. 692,754, filed

April 23, 1912. The principle of that invention was described in the said application as embodied in the best form then known to me.

The leading object of my present invention, is to adapt my invention disclosed in the aforesaid application, so as to produce a 30 complete and commercially practicable machine, in which and by which all the benefits of the invention can be fully realized. Some of the benefits thus sought may be briefly stated as follows: simplified construction of

35 the machine, involving very few parts and the elimination of all collector brushes or moving contacts between the primary of the generating coil and the interrupter contacts, the possible operation of the machine at 40 very high efficiency; the arrangement of the parts so that by removing the minimum number of fastening devices all the important and necessary parts may be immediately exposed for testing or repair, and if desired 45 the entire machine may be disassembled without risk and with the certainty of successful reassembling away from the shop; the complete inclosure and protection of the working parts; increasing the degree of insulation 50 between parts having a difference of potential in operation; the solid connection and automatic combined adjustment of the circuit breaker and its associated coil struc-

ture, whereby the advance and retard of the spark will be accompanied by a corresponding adjustment of the circuit breaker; etc. 55

In the accompanying drawings illustrating the invention, the complete specific design and combination of parts is shown, but many features and details of the construction herein disclosed may be applied to any machine of this general type, and especially to any machine having its windings carried on a movable secondary field structure in such a manner that the flux through said 60 windings is varied for the purpose of generation. It should be clearly understood therefore, that while this is a detail case, disclosing specific combinations as well as specific forms, nevertheless I am not to be 65 limited to the said specific combinations, and I contemplate all such non-essential variations and changes therein or in the individual parts, as may fairly fall within the scope of this statement of invention and the appended claims. 75

Referring to the drawings, Figure 1 is a vertical, longitudinal sectional view through a machine embodying my invention. Fig. 2 is a sectional view at right angles to Fig. 1. 80 Fig. 3 is an end elevation of the magneto with parts of the casing broken away to show the interior parts, and with the interrupter mechanism casing shown in section. Fig. 4 is a side view of the magneto with 85 side plate removed.

The same figures of reference denote the same parts wherever they are shown.

1 denotes a permanent field magnet supported by, but not attached to, the usual base 90 plate 2, which is itself commonly attached to the engine frame and carries the entire magneto. The polar extremities of 1 have suitable apertures in which are carried rotor end plates 3 and 4 which support shafts 5 95 and 6 carrying the rotors 7 and 8 which are magnetically separated from each other by non-magnetic block 9. Ball bearings 10 and 11 or other suitable bearings are provided in the end plates for the shafts of the rotor. 100

The end plates 3 and 4 are spaced apart by the non-magnetic rings 12 and 13, between which a core structure is clamped, comprising shoes 14 and 15 and core member 16 supporting generating windings 105 which usually consist of a primary 17 and

secondary 18. One end of each winding is "grounded" or connected to the core in the usual manner.

Supported on the end plate 4 and movable therewith, is an interrupter mechanism 5 housing 19 inclosing interrupter contacts 20 and 21, the latter movable and operated by cam 22 mounted on shaft 5. Shaft 6 carries a gear 23 engaging gear 24 carrying the distributor brush 25 which in a well known manner distributes the high tension current to segments such as 26 and 27 whereby said current is properly distributed to the spark plugs of the several cylinders when the magneto is used on a multi-cylinder engine.

15 The circuits connecting the primary and secondary coils, the distributor, the interrupter contacts 20 and 21, and the condenser 28 bridged across said contacts, are well known and I therefore do not show and describe the same, although herein-after I shall refer to the improved means by which these various circuits are connected with the various parts of the apparatus without the usual flexible wires or brush devices heretofore employed.

20 It is obvious from a study of the figures and the foregoing description, that the magnets support the rotor, the field structure 30 carrying the windings and the interrupter mechanism, and that these parts are not connected to the base in any way and are therefore freely removable. To securely clamp these parts in operative position on 35 the base, I employ side plates shown at 29 and 30, flanged at their upper portions so as to engage and overlap the edges of the magnets, and secured to the base by means of strips 31 and 32 held by screws 33 and 34 or in some other suitable manner. To 40 secure the top portions of these side plates together, a bolt 35 or other suitable means may be employed. The side plate 36 carrying the distributor mechanism is attached 45 to the base by screws or equivalent means.

45 It will be seen from the foregoing that to remove the magnets or rotor structure it is necessary only to take off the distributor plate 36 and the side plates 29 and 30 and 50 lift the working parts of the machine off the base which need not be removed from the engine.

55 It is often necessary to examine the windings, and I provide means for accomplishing this without removing the side plates 29 and 30, in the form of a cover 37, which may be separately removed by loosening nut 61, thereby permitting the secondary field structure carrying the windings to be 60 turned to the right, and the coil removed by pulling the core 16 carrying the same from between the jaws of the pole shoes 14 and 15, and bringing it out through the opening.

65 The core 16 is normally held in position

by means of a connector 38 which is held under a screw 39 on the head of the coil structure at one end and under a screw 40 insulated from the ring 12 on the other. This terminal 40 also connects to the core 70 42 of the insulated bridge piece 41 which carries the circuit from the primary winding of the coil connected to 39, to the terminal 43 which is insulated from casing 19, and which connects by any suitable means 75 such as the wire 44 to the fixed contact 20 of the interrupter, it being understood that this contact 20 is suitably insulated from the interrupter casing.

80 The secondary circuit is led out of the secondary coil and connected to a support 45 carrying a small roller 46 adapted to bear against and contact with the sector 47 connected to a terminal 48 for the connector 49 which carries the high tension current 85 to a socket 50 connected in any suitable manner such as by conductor 51 to the distributor contact 52 where brush 25 carries the current to distributor block 53 whence it is distributed to the various segments indicated at 26 and 27, as the distributor revolves. Sector 47 also connects to an insulated point 54, which is opposite a point 55 located on one of the end plates, this providing a safety gap or "ground" for the 90 high tension current. The safety gap contact 54, sector 47, and the terminal 48 for conductor 49, are all carried on a block of insulation 56 held in the bend of the magnet in any suitable manner such as the bolt 35, 100 which also clamps the side plates together at the top. The outwardly pressed portions or extensions 57 in plate 29, and in the door 37 in plate 30, permit the field structure carrying the windings to be moved angular 105 in relation to the poles of the magnet, around the center of rotation of rotor elements 7 and 8, thereby advancing and retarding the spark. To readily move this secondary field structure the lever 57 is provided, attached 110 between the interrupter casing and the magnets 1, or between the interrupter and a projecting flange 58 of the base. This can also be a projection on the casing 19.

115 It will be seen that the interrupter mechanism may be removed entire from the end of the shaft 5 by simply loosening the terminal 43 and screw 59 which clamps the casing to the shoulder on end plate 4. It will also be noted that the coil can be removed, and after its removal, the strength of the magnets can be roughly ascertained by placing a suitable piece of iron across the jaws of the field shoes 14 and 15 between which the core 16 normally fits, as by revolving the rotor, the flux is reversed and the strength of the same roughly indicated by the strength of pull on the piece of iron.

120 The distributor plate carrying the entire distributor comprising brush, 25, distributor 130

block 53, cover 60 and its associated parts together with distributor gear 24 and ball bearings 62 for same, may be removed from the machine by simply pulling out connector 5 49, and removing the screws 63. The distributor gear 24 is pressed on the outer cone of the ball bearing 62, while the inner cone is carried on block 64. Screw 65 clamps block 64 to a shouldered plate 66 attached 10 to the plate 36. The distributor block 53 is carried on the outer face of gear 24 by pins 67 and carries two brushes the center one 25 carrying current to one off center, which distributes to the segments 26, 27, 15 as the gear 24 revolves.

My improved construction eliminates all brushes and sliding contacts of any nature between the primary of the coil and the interrupter contacts and condenser, it being 20 understood that the condenser 28 is located in the cap of the interrupter mechanism and is connected in any suitable manner in multiple with or shunt of the contacts 20 and 21. As there are several well known methods of 25 connecting the condenser, I will not describe same. It will also be observed that I have eliminated all moving wires between the various parts. I have located the safety spark gap inside the bend of the magnet 30 where it is out of the way, and have provided a simple and direct path for the high tension current from the secondary winding to the distributor.

Having thus described my invention what 35 I claim and desire to secure by Letters Patent is—

1. In a dynamo, generating windings, a rotor and a core structure for the windings, a base carrying the same, a bridge extending 40 over and inclosing all said parts, with its ends resting upon the base, and side plates clamped to the bridge and the base and covering the lateral openings beneath the bridge.

45 2. In a dynamo, a field structure, a generating coil and a rotor operatively associated therewith, said field structure supported on the base and forming therewith a closed figure with open sides within which the other 50 parts are housed, and side plates covering the side openings, secured to the base and engaging the field structure so as to clamp the same to the base.

3. In a dynamo, a base, an inverted U-shaped field structure supported on said base, a rotor and generating windings mounted within the field structure, and side plates secured to the base and fitting over the edges of the field structure, so as to 55 clamp the same securely to the base and at the same time completely cover and inclose the working parts of the machine.

4. In a dynamo, a base, an inverted U-shaped magnetic field structure supported 60 thereon to form a bridge, a rotor and gen-

erating windings within and beneath the bridge, and side plates secured to the base and extending up into overlapping engagement with the field structure, so as to clamp the same to the base.

5. In a dynamo, a base, an inverted U-shaped magnetic field structure supported thereon to form a bridge, a rotor and generating windings within and beneath the bridge, and non-magnetic metal side plates 70 secured to the base and extending up into overlapping engagement with the upper part of the magnet structure so as to close the open side of the bridge, fully inclosing the working parts therein and also clamping the entire structure firmly to the base.

6. An ignition dynamo comprising a base, primary field magnets supported thereon, a rotor and secondary field structure supported upon and within said magnets, and 85 a pair of flanged cover plates secured to the base and extending over both sides of the magnets with their flanges overlapping the edges thereof so as to clamp the magnets and inclosed parts to the base.

7. An ignition dynamo comprising a base, U-shaped permanent field magnets supported thereon, a generator coil and secondary field structure therefor vertically supported within said magnets at right angles thereto, a rotor comprising a pair of inductor elements extending through and between the magnet poles and adapted in rotation to conduct the flux from each magnet pair alternately to the two poles of the 100 secondary field, and a pair of flanged cover plates inclosing said magnets and having flanges clamping the same to the base.

8. An ignition dynamo comprising a base, U-shaped permanent field magnets supported thereon, a generator coil and secondary field structure therefor vertically supported within said magnets at right angles thereto, a rotor comprising a pair of inductor elements extending through and 105 between the magnet poles and adapted in rotation to conduct the flux from each magnet pair alternately to the two poles of the secondary field, and a pair of flanged cover plates inclosing said magnets and having 110 flanges clamping the same to the base, said cover plates each having an opening with extension covers therefor, adapted to permit adjustment of the secondary field in either direction.

9. An ignition dynamo comprising a base, U-shaped permanent field magnets supported thereon, a generator coil and secondary field structure therefor vertically supported within said magnets at right 115 angles thereto, a rotor comprising a pair of inductor elements extending through and between the magnet poles and adapted in rotation to conduct the flux from each magnet pair alternately to the two poles of the 125 120 secondary field, and a pair of flanged cover plates inclosing said magnets and having flanges clamping the same to the base.

- secondary field, and a pair of flanged cover plates inclosing said magnets and having flanges clamping the same to the base, said cover plates each having an opening with extension covers therefor, adapted to permit adjustment of the secondary field in either direction, and one of said extension covers being detachably secured to its plate, so as to permit ready access thereto and to the field structure and connections, for the removal and testing of the coil and other parts.
10. A magneto machine for ignition systems comprising the following instrumentalities: a permanent field magnet structure, a rotor, generating windings and a secondary field structure therefor mounted within and between the field magnet poles, and adjustable around the axis of rotation of the rotor, an interrupter mechanism supported outside of one of the field magnet poles, and a circuit connection from the generator winding to the interrupter comprising a stiff metal strip or bar secured at one end to the coil and at the other end to a solid terminal supported on the coil structure in proximity to the rotor, a corresponding solid terminal outside the magnet pole on the interrupter mechanism, and an inverted U-shaped solid connecting bar bridging said terminals around the magnet pole, and adapted to move in an arc to one side of said magnet pole upon rotary adjustment of the coil and secondary field on the interrupter.
15. 11. A magneto machine for ignition systems comprising the following instrumentalities: a base, an inverted U-shaped permanent field magnet structure supported on said base, a rotor, generating windings and a secondary field structure therefor, all mounted within and between the poles of said field magnet, said coil and its structure being adjustable around the axis of rotation of the rotor, an interrupter mechanism rotatably supported on the outside of one of the magnet poles, and a circuit connection from the generating coil to the interrupter comprising a stiff metal strip or bar secured at one end to the coil and at the other end to a solid terminal supported on the coil structure in proximity to the rotor, a corresponding solid terminal outside the magnet pole on the interrupter mechanism, and an inverted U-shaped solid connecting bar bridging said terminals around the magnet pole, and adapted to play in an arc to one side of the magnet pole during rotary adjustment of the coil and its structure and the interrupter, and side plates covering the open space between the limbs of the primary field magnet so as to inclose all the working parts except the interrupter, one of said side plates having an opening adapted to permit travel of the generating coil structure in its adjustment, through the plane of said plate, and also to permit corresponding travel of the said U-shaped connecting bar.
20. 12. A magneto machine for ignition systems comprising the following instrumentalities: a base, an inverted U-shaped permanent field magnet structure supported on said base, a rotor, generating windings and a secondary field structure therefor, all mounted within and between the poles of said field magnet, said coil and its structure being adjustable around the axis of rotation of the rotor, an interrupter mechanism rotatably supported on the outside of one of the magnet poles, and a circuit connection from the generating coil to the interrupter comprising a stiff metal strip or bar secured at one end to the coil and at the other end to a solid terminal supported on the coil structure in proximity to the rotor, a corresponding solid terminal outside the magnet pole on the interrupter mechanism, and an inverted U-shaped solid connecting bar bridging said terminals around the magnet pole, said bar adapted to play in an arc to one side of the magnet pole during rotary adjustment of the coil and its structure and the interrupter, and side plates covering the open space between the limbs of the primary field magnet so as to inclose all the working parts except the interrupter, one of said side plates having an opening adapted to permit travel of the generating coil structure in its adjustment, through the plane of said plate, and also to permit corresponding travel of the said U-shaped connecting bar.
25. 13. In a dynamo electric machine, a base, a magnetic field structure supported on said base, a rotor and generating windings inclosed within the space between the field poles, and covers or closures for said space extending across the field structure on each side and secured to the base so as to hold the field structure and working parts firmly thereto.
30. 14. In a dynamo electric machine, an inclosing field structure having open sides, a base supporting the same, a rotor and generating windings in operative relation to said field structure, and a pair of clamping plates securing the magnet structure to the base and shaped so as to inclose and protect the working parts.
35. 15. A dynamo electric machine comprising a field structure, a base supporting the same, a rotor, a secondary field or magnetic circuit operatively associated with the rotor,

a detachable coil supported on said secondary field, and means on the primary field structure for holding said coil in place, said field structure itself being clamped to the base by means of side plates, whereby detachment of the side plate fastenings permits all parts to be disassembled.

16. In an ignition dynamo, primary field magnets, a secondary field structure having 10 adjustable poles, and means associated with the primary field for directing the flux therefrom through said secondary poles alternately and oppositely, and a lever connected to the secondary field, and adapted 15 when moved to turn the same so as to effect an angular displacement of the secondary field poles to advance or retard the spark.

17. In an ignition dynamo, primary field 20 magnets, a secondary field structure having adjustable poles, and means associated with the primary field for directing the flux therefrom through said secondary poles alternately and oppositely, and a lever connected to the secondary field, and adapted when moved to turn the same so as to effect 25 an angular displacement of the secondary field poles to advance or retard the spark, together with an interrupter mechanism mechanically connected to and movable with 30 said secondary field poles, whereby the single adjusting lever moves all the related parts as one unit.

18. In an ignition dynamo, the combination 35 with the following instrumentalities: a field magnet structure having poles spaced apart from each other, a generating winding and a secondary field structure therefor with poles in the space between the primary 40 field poles, a rotor composed of magnetically insulated opposite inductor elements mounted on connected shafts extending through the primary field poles, flanged bushings containing bearings mounted in the primary 45 field poles with other flanges inside the same and constituting journal boxes for the rotor shaft ends, mechanical connections from the secondary field poles to the flanges on said bushings, securing the same together 50 as one unit, and a lever secured to one of said bushings outside of the primary field pole through which it passes, and adapted to rotate the same together with the secondary field structure and the connected parts, all as one unit, for the purpose of timing 55 the spark delivered by the machine.

19. In an ignition dynamo, the combination 60 with the following instrumentalities: a field magnet structure having poles spaced apart from each other, a generating winding and a secondary field structure therefor with poles in the space between the primary field poles, a rotor composed of magnetically 65 separated opposite inductor elements mounted on connected shafts extending

through the primary field poles, flanged bushings containing bearings mounted in the primary field poles with other flanges inside the same and constituting journal boxes for the rotor shaft ends, mechanical connections from the secondary field poles to the flanges on said bushings, securing the same together as one unit, and a lever secured to one of said bushings outside of the primary field pole through which it passes, 70 and adapted to rotate the same together with the secondary field structure and the connected parts, all as one unit, together with a casing rigidly mounted on the outer end of said bushing, and receiving the end 75 of the rotor shaft journaled in and extending through said bushing, interrupter mechanism carried in said casing, and an actuating cam therefor secured on the end of said rotor shaft, whereby movement of the lever 80 will not only angularly adjust the secondary field poles by rotating the bushings, but will simultaneously adjust the position of the interrupter contacts with respect to the actuating cam, for the purpose of correctly 85 timing the spark delivered to the machine.

20. In an ignition dynamo, field magnets 1, a generating coil and related parts in the space within the limbs of the field magnet, and a pair of cover plates 29 and 30 extending over and entirely covering the side openings between said limbs, a base carrying the magnets and contained parts and having the cover plates secured thereto, a metal rod 35 extending through the space within 90 the field magnet from side to side, and means for securing the cover plates rigidly thereto.

21. In an ignition dynamo, field magnets, an adjustable generating coil in the space 95 within the magnets, an insulating block mounted between the side limbs of the field magnets and above said coil, a fixed contact on said block, and a movable contact carried on the coil, together with circuit connections completed through said contacts.

22. In an ignition dynamo, field magnets, side plates, an adjustable generating coil in the space within the magnets and secured to the side plates, an insulating block mounted between the side plates and above said coil, 105 a fixed contact on said block, and a movable contact secured to the coil and adapted to travel over and maintain circuit connection with the fixed contact throughout the arc of adjustment of the generating coil, circuit 110 connections for said coil being completed through said contacts in all positions of the coil.

23. In an ignition dynamo, field magnets, an adjustable secondary field structure and 115 a detachable generating coil associated therewith in the space within the said magnets, an insulating block mounted within the magnets above the coil, an arc-shaped friction strip secured on the block and hav- 120 125 130

- ing its center of curvature coincident with the center of arc of adjustment of the coil, and an anti-friction traveler on the coil making contact with said friction strip in all 5 positions of the coil throughout its normal arc of movement, whereby said coil is at all times held against displacement from the secondary field poles with which it is associated.
- 10 24. In an ignition dynamo, field magnets, a generating coil and secondary field structure in the space within said magnets, said coil being detachable from said secondary field structure, an insulating block mounted 15 within the magnets and above the coil, an arc-shaped metal strip on said block, and a contact traveler on the coil and constituting a terminal thereof, said traveler and said strip remaining in contact through the normal arc of travel of the coil and related 20 parts, thereby mechanically holding the coil in position and electrically maintaining the circuit during said travel.
- 25 25. In an ignition dynamo, field magnets, a generating coil and secondary field structure in the space within said magnets, said coil being detachable from said secondary field structure, an insulating block mounted 30 within the magnets and above the coil, an arc-shaped metal strip on said block, and a contact traveler on the coil and constituting a terminal thereof, said traveler and said strip remaining in contact through the normal arc of travel of the coil and related 35 parts, thereby mechanically holding the coil in position and electrically maintaining the circuit during said travel, together with means for normally limiting the travel of the coil and related parts in adjustment, but 40 adapted to permit continued movement when desired, to disengage said contact traveler from the strip and thereby break the circuit and permit removal of the coil from the secondary field structure.
- 45 26. In an ignition dynamo, field magnets, an inclosed generating coil and secondary field structure, an insulating block inside the upper portion of the field magnets and a terminal, with a spark gap for limiting the 50 operative potential, carried on said block.
- 55 27. In an ignition dynamo, a field magnet structure, side plates covering the sides thereof so as to inclose a space, an insulating block mounted in said space between the side plates, and a safety spark gap and terminal countersunk in said block.
- 60 28. In an ignition dynamo, permanent field magnets, an adjustable generating coil, a fixed contact terminal for said coil, and 65 means carried on the coil and traveling over said fixed contact for conducting current directly from said coil to said terminal in all positions of the coil throughout its range of adjustment.
- 70 29. In an ignition dynamo, field magnets, an adjustable generating coil and related parts mounted in proximity to said field magnets, an insulating block containing a channel or cavity, a fixed contact strip in said channel, and a coöperating contact carried on the coil and traveling in the channel over said fixed strip as the coil is adjusted, the circuit of said coil being completed through said contacts.
- 75 30. In an ignition dynamo, field magnets, a generating coil and coöperating parts mounted in adjustable working relation to said field magnet, an insulated terminal block mounted on said magnet and provided with a channel or cavity, a fixed contact strip 80 mounted in the bottom of said channel, and a movable contact traveling on the same and extending out of the channel into operative connection with the movable coil, whereby for all positions of the coil the working contacts are protected and insulation maintained at a high point.
- 85 31. In an ignition dynamo, a field magnet structure, generating windings and a power shaft, a pinion mounted on said shaft, a gear meshing with said pinion, a fixed casing about said gear, a distributor disk connected with said casing, a plurality of contacts carried by said disk, a moving contact coöperating therewith, a connection between 90 said moving contact and said gear, and ball bearing journal connections for said gear on the casing, whereby power from the shaft is transmitted through the pinion and gear to the traveling contact of the interrupter 95 without friction.
- 100 32. In an ignition dynamo, a field magnet structure, a generating coil with a rotor and power shaft, a pinion 23 on the power shaft, a gear wheel 24 meshing therewith, a supporting plate or casing rigidly attached to the field magnet structure, two-part annular ball bearings, having one part or ring associated and connected with the gear wheel, a central block carrying the other part of the 105 ball bearings, and a fastening device extending through said central block securing the same and thereby the ball bearings firmly to the frame or casing, together with a distributor disk secured to the casing and contacts carried thereby opposite the gear wheel, with a coöperating movable contact secured to but insulated from the gear wheel, and movable thereby to shift the circuit of 110 the generating coil to the said contacts in succession as the power shaft rotates, the removal of the said distributor disk and the said single fastening device permitting the detachment of the gear wheel with the entire 115 ball bearings.
- 120 33. In an ignition dynamo, field magnets and coöperating generating parts, a power shaft therefor, and a distributor mechanism associated therewith comprising the following instrumentalities: a plate or support 125 130

a hollow disk 60 or insulating material secured on said support, a pinion 23 on the power shaft, and a gear wheel 24 meshing with said pinion and underlying the said insulating disk, a two-part annular ball bearing having an inner and an outer concentric ring with a raceway between them for the balls, said rings extending parallel to each other at right angles to the gear wheel 10 and lying within a recess formed therein, an opening in the casing concentric with but of greater diameter than the outer ring of the ball bearings, a back plate 66 receiving the thrust of both rings on its face and having 15 an annular flange extending into the space between the outer ring and the casing, a central block 64, and a screw 65 extending therethrough and tapped into the back plate, together with a movable contact 25 lying within the hollow of the insulating disk or block 60, and secured to the gear wheel 24 so as to be rotated thereby, the construction being such that by removing the block 60 and the screw 65, the gear 25 wheel and associated parts will all come away as a unit including both parts of the ball bearings.

34. In an ignition dynamo, a field structure, a power shaft and generating parts, a base carrying the same, a support 36 secured to the base, a pinion secured on the power shaft and a gear wheel journaled on said rigid support, together with an insulating block overlying the gear wheel and carrying distributing contacts adapted to be actuated by said gear wheel.

35. In an ignition dynamo, a magnetic field structure, a rotor and a detachable generating coil, together with a fixed contact carried by but insulated from the field, a coöperating traveling trolley contact carried on the coil and electrically connected thereto, and a spark gap and distributor connected to the coil through said contacts, said coil being also mechanically held in place thereby.

36. In an ignition dynamo, a field and a detachable movable generating coil, in com-

bination with a trolley contact for said coil, adapted to complete the circuit connection 50 of said coil and also mechanically hold the coil in position.

37. In an igniton dynamo, permanent field magnets having their opposite limbs substantially parallel, a generating coil and 50 a power driven shaft with rotor connections, said shaft passing through and journaled in bearings in the magnet poles, and a distributor mounted on the outside of and parallel to one magnet limb, with driving gear 60 connections to said power shaft.

38. An ignition dynamo comprising a permanent magnetic field structure with a power shaft journaled in bearings in its opposite limbs, a rotor and generating coil 65 between the limbs, an interrupter outside of one limb carried on said limb and connected to the power shaft, and a distributor outside the other limb carried on said limb and connected to the power shaft. 70

39. An ignition dynamo comprising a permanent magnetic field structure with a power shaft journaled in bearings in its opposite limbs, a rotor and generating coil between the limbs, an interrupter outside 75 of one limb carried on said limb and connected to the power shaft, and a distributor outside the other limb carried on said limb and connected to the power shaft, together with side plates covering the space between 80 the magnet limbs and inclosing therein the rotor and generating coil, a housing for the interrupter mechanism, and an inclosure for the working parts of the distributor, whereby the entire magneto is tightly inclosed 85 and protected, but each of the parts is separately and easily accessible for inspection or repairs without disturbing any of the other parts.

In testimony whereof I hereunto affix my 90 signature in the presence of two witnesses.

CHARLES THOMAS MASON.
